UNITED STATES PATENT OFFICE

GRANVILLE F. GIBSON, OF SHREVEPORT, LOUISIANA

COIN HANDLING MECHANISM FOR VENDING MACHINES, TELEPHONES, ETC.

Application filed February 5, 1931. Serial No. 513,679.

The object of this invention is to provide coin handling mechanism for use in connection with telephone instruments installed at pay stations, and for use in connection with vending machines of the type disclosed in my U. S. Patent Number 1,780,124,—the present case pertaining especially to the coin receiving and handling devices, and to the locking mechanism to be described.

10 A further object is to extend the scope of usefulness of the device, commercially, and to provide for a high degree of efficiency in operation.

With the foregoing and other objects in view, the invention consists in the novel construction and arrangement of elements described illustrated and claimed, it being understood that modifications may be made within the scope of the claims without departing from the spirit of the invention.

In the drawings,

Figure 1 is a view of the machine in front elevation.

Figure 2 is a vertical section on line 2—2 of Figure 1.

Figure 3 is a vertical section on line 3—3 of Figure 2.

Figure 4 is a vertical section on line 4—4 of Figure 2.

30 Figure 5 is a detail view, in section on line 5—5 of Figure 1.

Figure 6 is also a detail view, in section, showing the structure above the central portion of Figure 2.

35 Figure 7 is a horizontal section through the coin chute.

Figure 8 is a perspective view of the chute, looking from the rear.

Figure 9 shows a part of the structure of 40 Figure 6, from the other side.

Figures 10 and 11 illustrate details described below.

The housing of the machine includes the top 10, and bottom 11; also the side walls required for a complete closure.

The mechanism of the machine is composed of the following assembled units, detailed description of which follow in order:

50 A hand lever, for operating the machine; a chute for holding a plurality of coins of like

denomination; mechanism for forcing the desired number of coins thru the chute, and devices controlling delivery.

A lever 16 on the outer portion of the machine is mounted on shaft 17, having a bearing in bracket 18, as shown in Figure 3, movement being limited by stop 19 of Figure 1.

55 Shaft 17 mounts a lever 20 having a lug or engagement portion 21 thereon, and a series of teeth adapted for engagement by a pivoted locking dog, or safety device 23, normally positioned as in Figure 2 by opposed springs 24 and 25. This dog prevents attempts at fraudulent operation from being successful when the machine is in operation by pulling the lever down just far enough for the merchandise to be delivered without forcing the coin out of the chute, then letting the lever return to normal position and starting the operation all over again.

60 The coin chute of Figures 1, 7 and 8 of the drawings, is positioned on the outside of the front wall of the machine, as in Figure 1, being detachable. It is shown in perspective in Figure 8 and in horizontal section in Figure 7, and a chute of the size required for a given coin will be employed, the operation of shifting to another chute, when the conditions (selling conditions) are changed, being facilitated by pivoted and slotted catches 38 of Figure 4, which engage screws 39 of Figure 8.

65 The coin chute includes sides 40 and 41, engaging and retaining the front plate 42 of glass. The chute further includes inclined portions 43, a rear plate 44 and guiding plates or strips 45, 46. The coin is admitted between the edges of strips 44', and an elongated spring 47 (Figure 5), of small gage wire, acts to throw a coin or a slug of smaller diameter than the coin for which the chute is intended, outwardly into the clear space 48, where it drops to the deflecting device 49 of Figure 2, and passes below the glass front plate into pan 50, indicating that 70 no operation of the machine can result from a coin of that denomination.

75 Coins operating the machine forcibly strike bell B after passing thru the coin chute C into receptacle C'.

Near the top or upper part of the chute is an offset from the chute forming a pocket 55, extending upwardly to the top end of the chute, fitting closely under the overhanging edge portion or member of top 10. On the top surface of top 10 and in line with pocket 55 and attached rigidly thereto, is a metal mouthpiece 55' thru which the coin is dropped into pocket 55. At the bottom of pocket 55 is an outlet leading into the main chute, thru which coins roll to fill the chute. When the coin chute is filled with coins to operation capacity, the top coin in the chute will be near the outlet of pocket 55.

If other coins are dropped or deposited in the pocket before the machine is operated, the first coin deposited will take the position within the pocket indicated by 56 in Figure 1, the lower edge of which rests against the top edge of the top coin in the slot, until the machine is operated, when the column of coins in the chute is forced downwardly, then the bottom coin in pocket 55 rests against the flat surface of element 65 until the return thereof to its upward normal position, when the coin or coins in the pocket roll thru the outlet into the main chute to take the place of the coins forced out.

The lower or bottom coin in the chute engages a pin or the like 58, passing thru curved slot 59 in element 44. This device 58 constitutes a crank on disk 60 by means of which the spring retained clutch shown conventionally at 61, is rotated or rocked, being limited in its motion by stop 61', and returned to its starting point after each operation by spring 60', Figure 4.

Thru the back 44 of the chute of Figure 8, is a cutaway portion 67a having a shoulder 67' and when the main chute is filled with coins (to operating capacity), the top coin bridges this cutaway portion.

The mechanism for ejecting coins from the chute includes a bar 70, to which there is rigidly attached an element 65 mounting a device 66 forming a finger, having its upper end pivoted to member 65, which permits the lower end of the finger to swing, this finger having a shoulder 67 and a heel 66'. This mechanism is positioned near the front wall of the machine and on the inner side of the housing, and communicates with the chute of Figure 8 thru the front wall of the housing.

Bar 70 operates vertically thru guides 71 and 71'. Also attached rigidly to bar 70 is an arm 69 including a portion 30 extending at a right angle, and on portion 30 there is mounted an element 28' having several apertures 28, to be referred to below.

Bar 70, element 65, finger 66, arm 69, carrying element 28' at its free end and guides 71 and 71' constitute the ejecting mechanism, by which coins are forced from the chute.

In Figure 4 shaft 76 is shown as being

mounted in suitable bearings. At one end of shaft 76 is rigidly attached finger 75 (Figure 2), and at the other end is rigidly attached crank arm 77 (Figure 4). Lever 31 (Figure 2), carrying a hooked dog 36 is pivoted to the side wall of the machine at 32, and hook 36 normally stands in the path of lug 21 on arm 20. Rod 34 forms connecting means between lever 31 and rocking arm 77, the points of pivotal connection being at 33 in Figure 2, and on arm 77 in Figure 4. Rod 34, having operative movement upwardly is returned to normal position by spring 35 pressing downwardly against a pin 34' in rod 34 at the lower end of the spring, and bearing on guide bracket 30' at its upper end.

Rod 27, (Figure 2) forms the connecting means between lever 20, and member 30 of arm 69.

Method of operation

To operate the machine, pull hand lever 16, Figure 1, which pulls down on rod 27, Figure 2, which in turn pulls the coin ejecting mechanism downwardly, bringing finger 66 in contact with finger 75. If the required number of coins have not been deposited, finger 75 engages finger 66 and brings shoulder 67 in contact with shoulder 67', locking the mechanism.

Spring 35 pushes downward on rod 34, and rod 34 presses lever 31 downwardly, forcing hooked dog 36 in the path of lug 21 of lever 20, forming a second locking device and causing finger 75 to assume the position of Figure 2, in the path of finger 66. Incident to the downward thrust on rod 34, crank arm 77, rock shaft 76 and finger 75 are actuated, in attaining the position indicated. If lever 16 is operated without the proper number of coins in the chute, finger 66 on coin ejector 65 is forced by finger 75 through cutaway portion 67a, and shoulder 67 engages shoulder 67', preventing further movement of ejector 65. Dog 36 remains in the path of lug 21, because finger 75 is not moved unless finger 66 is forced to the left by a coin bridging cutaway portion 67a (Figure 6). When lever 16 is released, coin ejector 65 rises under the action of spring 73, and finger 66 is forced to the left by cam surface 78 on said finger 66 engaging cam surface 79 on the coin chute (Figure 2)—the movement of finger 66 to the left clearing the outlet in the bottom of the coin pocket 55 of Figure 1 leading to the coin chute.

In case a coin or slug is deposited which is of smaller diameter than the coin for which the chute is intended, and when the machine is regulated to operate on a single coin as payment for one purchase, heel 66' on finger 66, will on its downward course push such coin or slug out of the coin chute into the clear space 48, so that it drops into the pan at the bottom of the chute. The chute remains filled, save for the coin or coins ejected.

at each operation. The number ejected is determined as indicated below.

When two or more coins are forced out, a small coin or slug would lodge in the chute 5 out of reach of the action of finger 66, were it not for spring 47 which throws them out of the chute, to be returned to the party who deposited them.

If the slot has the required number of 10 coins, as in Figure 1, the top coin bridging the cutaway portion 67a, Figure 8, finger 66 will cross the cutaway portion, heel 66' of finger 66 swinging the finger by engagement with the upper coin in the vertical column of 15 coins, and causing shoulder 67 of the finger to move out of the path of shoulder 67', permitting the ejecting mechanism to move downwardly. This movement of finger 66 by engagement with finger 75 on shaft 76 20 causes crank arm 77 on that shaft to lift rod 34 against the normal downward thrust of spring 35.

Lever or locking member 31 is thus raised and its hooked dog 36 is lifted out of the path 25 of lug 21 on the disk portion of lever 20.

The locking device is now free, but as soon as the locking device has been freed and the ejecting mechanism starts down, forcing the 30 column of coins in the chute before it (and before the lower coin in the coin chute is forced out of the chute), dog 23, Figure 2, engages the first tooth of lever 20, preventing lever 16 and the ejecting mechanism from returning to their upward normal positions 35 until lever 16 has touched stop 19, thereby forcing out of the slot the required number of coins. At this time dog 23 breaks contact with the last tooth on lever 20, and the large coiled spring 73 (Figure 4), which is attached to lever 20 at 74, with its upper end secured at 74 to a stationary element, pulls the lever upward to a normal position, and at the same time pushes upward on rod 27 40 which lifts member 30 of arm 69, raising the ejecting mechanism to its normal position.

The downward stroke of the ejecting mechanism may be varied in its length by shifting rod 27 at its bottom and top portions, to the various apertures in lever 20 and element 28'. 50 If shifted to the left hand aperture indicated by 26 in lever 20, and to the left hand aperture indicated 28 in arm or element 28', the machine will operate on a single coin; if shifted to the middle apertures, bottom and 55 top, it operates on two coins, etc. Each shift of rod 27, adds another coin to the purchase price, or reduces the number of coins required, depending on the direction of the shift.

In Figures 2 and 8, the element 60a is to be 60 considered as effecting connection between clutch member 61 and an article delivery device to be supported in bearings at 60b carried by frame 60c.

As a modification,—in Figure 11, a telephone circuit or the like is to be closed when 65

clutch member 61 actuates a switch S assumed to be in the circuit S' to be controlled.

What I claim is:—

1. In a machine of the class described, a 70 coin chute, means for temporarily retaining a plurality of coins in the chute, coin feeding means, a lever connected with the coin feeding means, and coin controlled locking means preventing movement of the feeding means and lever and including an engaging element carried by the feeding means and positioned to engage a stationary member, means on the engaging element controlled by one of a predetermined number of coins, for releasing the engaging element, a dog positioned to engage and release the lever, and means controlled by said engaging element for releasing the dog. 75

2. A machine comprising the elements of 80 claim 1, and independent means for engaging the lever and preventing the operation of the machine when the stroke of the lever is less than a predetermined stroke. 85

3. A vending device including the elements 90 of claim 1, and mechanism for positively actuating the dog for producing engagement thereof with the lever. 95

4. In a vending machine, a chute including a main portion affording space for a predetermined number of coins, and including an offset portion for surplus coins, coin ejecting means for engaging and imparting thrust to the upper coin in the main portion of the chute, locking means for the ejecting means, said locking means including an element movably connected with the ejecting means and controlled by the upper coin of said predetermined number of coins in the chute, and supplemental locking means operatively connected with and released by the locking means first named. 100 105

5. A machine comprising the elements of 110 claim 1, and means determining the effective stroke of the lever and the extent of movement of the coin feeding means.

In testimony whereof I affix my signature. 115
GRANVILLE F. GIBSON.
